UNITED STATES PATENT OFFICE

JAN VOJÁČEK, OF PRAGUE, CZECHOSLOVAKIA

GARAGE

Application filed June 12, 1928, Serial No. 284,781, and in Czechoslovakia February 11, 1928.

This invention refers to parking arrangements, garages or storage buildings for storing motor vehicles, the principal object being to provide the maximum storage space while permitting the vehicles when coming out of their stalls, to continue in the same direction of travel in which they entered the stalls, so that there is no backing of vehicles.

The single figure of the accompanying drawing shows a plan view of the garage according to the present invention.

The garage comprises a continuous helical belt of diagonally arranged stalls disposed therein, and three helical gangways.

15 The stalls are arranged in a continuous spiral belt and communicate on both ends directly with the low spiral ways 32 and 33. The third spiral way 34 is placed preferably inside the inner spiral 33, it can however surround the outer spiral 32 instead, and has an inverse twist in relation to the spirals 32 and 33. The spirals 34 and 33 are interconnected by openings 35 which are placed wherever these two spirals intersect one in the same 20 horizontal plane. In order to facilitate the passage of cars from one spiral to the other, sectors 34, and if desired also sectors 33' and 32', corresponding in altitude and in circumference to the openings 35, are horizontal. 25 The third spiral 34 may, but need not necessarily, have the same number of threads and the same pitch as spirals 32 and 33. In the former case the openings 35 are placed all in one vertical column but the gradients of the 30 spirals differ considerably, whilst in the latter case the gradients of the spiral 34 can be chosen equal to, or even easier than, the gradient of the adjacent spiral 33.

The spirals 32, 33 and 34 need not be circular, but can have in ground-plan any suitable outline which secures the best utilization of the given building-lot. Especially the outer spiral way 32 can have a polygonal outline, preferably with rounded off corners, 45 adapted to the outlines of the building lot: if the inner spirals 33 and 34 are circular or elliptical, this arrangement gives the advantage of stalls 31 of unequal length, which are thus suitable for parking vehicles of different 50 length and size, without any space wasted.

The spaces 36, 37 can be used for stairs, lifts, cloak-rooms, stores, offices, repair-workshops, etc.

It is evident that the spiral 34 can be used by ascending and the spirals 33 and 32 by descending, vehicles, or vice versa, without any change in the inner arrangements being needed. In the former case a car having the stall 31' will enter the building at 38, ascend by spiral 34 up to the platform 34' which is next 55 highest to its stall, pass through the opening 35 onto the platform 33', descend without backing or changing the direction of travel along the spiral 34, and enter its stall 31'. The same car leaving the garage, will continue in 60 the original direction of movement from its stall 31' on to and along, the spiral 32, and leave the building at 39. In the latter case this procedure will be reversed, the car entering the building at 39, ascending along the 65 spiral 32 to its stall 31', then continuing along the spiral 33 to the next opening 35, passing through the latter on to and descending along, the spiral 34, and leaving the building at 38.

Claim:

A plural-storied garage having a continuous helical belt of diagonally arranged stalls disposed therein, a helical entrance gangway communicating with the entrance ends of the stalls, a helical gangway inclined in the same 75 direction as the entrance gangway and communicating with the exit ends of the stalls, a third helical gangway inclined in the opposite direction to the two above named gangways and disposed adjacent to one of the two 80 above named gangways, the last named third gangway communicating with that of the first named two gangways to which it is adjacent, at places at which these two gangways adjacent to each other intersect one 85 above named gangways, the last named third gangway communicating with that of the first named two gangways to which it is adjacent, at places at which these two gangways adjacent to each other intersect one 90 and the same horizontal plane.

In testimony whereof I affix my signature.

JAN VOJÁČEK.
